SPARK ARRESTER (LOUVERED)

William F. Kiesel, Jr., Hollidaysburg, Pa.

Application March 15, 1938, Serial No. 196,075

14 Claims. (Cl. 110—122)

This invention relates to locomotive smoke box and stack construction and deals particularly with apparatus arranged within the smoke box and serving as a spark arrester and cinder cleaner for the box.

5 It is a general object of the present invention to provide a novel and improved smoke box, stack and spark arrester assembly for locomotives.

10 More particularly it is an object of the invention to improve the fundamental combination with a smoke box of inside smoke stack, flaring petticoat depending therefrom and coaxial cinder screen in alignment with and above the exhaust nozzle by supplying a superior form and arrangement of netting or screen for preventing the passage of large cinders up the stack.

15 It is a further object of the invention to provide, in the combination just described, a definite ratio between the total flue area of the boiler and the gas passage area beneath the lower edge of the petticoat to provide a sufficient velocity of flue gases thereunder to ensure a self-cleaning smoke box, i. e., one in which the cinders collected by the netting are continuously urged into the stack under the action of the velocity of these gases and therein broken and ejected.

20 An important feature of the invention consists in the provision of additional means interposed between the forward flue ends and the stack to act as a target for the cinders and sparks which pass through at least the lower flues, whereby they are broken by the impact and thrown upwardly, giving them additional time 25 for cooling and disintegration before they are drawn into the stack by way of the lower edge of the petticoat under the draft induced by the blower nozzles.

25 A further important feature of the invention consists in arranging the screen, which surrounds and extends above the lower nozzle and forms a continuation of the inside stack, in the form of a louvered cylinder comprising blades each set at a substantial angle to the corresponding tangent to the cylinder and extending generally vertically, whereby a spiral motion is imparted to the gases passing therebetween to assist in breaking up the sparks and cinders.

30 Other and further features and objects of the invention will be more apparent to those skilled in the art upon a consideration of the accompanying drawings and following specification, wherein are disclosed several exemplary embodiments of the invention with the understanding

that such changes, combinations of forms and variations may be made therein as fall within the scope of the appended claims, without departing from the spirit of the invention.

In said drawings:

Figure 1 is a longitudinal, central, vertical section through the smoke box and associated parts of a steam locomotive;

Figure 2 is a transverse section thereof taken on line 2—2 of Figure 1 and looking rearwardly, 10 the stack and associated parts being retained in elevation;

Figure 3 is a fragmentary top plan view of the louvered stack screen on an enlarged scale;

Figure 4 is a vertical section on line 4—4 of 15 Figure 3;

Figure 5 is a view similar to Figure 3 showing a modification of the upper end ring;

Figure 6 is an elevation of a modified form of 20 louvered stack screen;

Figure 7 is a view similar to Figure 6 of a further modification;

Figure 8 is a horizontal section on line 8—8 of 25 Figure 7; while

Figures 9 and 10 are elevations of still further modifications of stack screens.

In my prior Patent No. 1,749,487 for Smoke box and stack, there is disclosed a fundamental arrangement on which the present invention constitutes improvements. In that patent there 30 is disclosed the usual smoke box defined by an extension of the boiler barrel, the flue sheet and a front door. Supported on the top of this extension is the external stack, and depending therefrom is the internal stack extending substantially to the middle of the smoke box. From this depends a flaring petticoat which surrounds a cylindrical screen or netting extending from the lower end of the internal stack and fitting concentrically over the exhaust nozzle. The 40 netting is protected from direct impingement of cinders and sparks by the petticoat, under the lower edge of which everything ejected from the stack by the exhaust steam must pass. The screen prevents the passage of large cinders and 45 serves to break them up for future ejection.

The present invention makes use of the same fundamental combination and there is shown in Figures 1 and 2 the cylindrical extension 10 of the boiler barrel, at 11 the flue sheet supporting 50 the forward ends of the flues 12 and the front door 13, which parts define an enclosed space commonly known as the smoke box into which pass all of the exhaust products of combustion 55 from the flues. Supported from the shell 10 is

a stack 14 having a portion 15 external to the barrel and an inner portion 16, the lower end 17 of which is adjacent but above the mid-height of the barrel as shown in the drawings.

5 Supported from the cylinder saddle (not shown) and connected to the exhaust pipes from the cylinders is the exhaust nozzle 18 which may take one of the forms disclosed in my prior Patent No. 1,726,152 for Exhaust nozzle. This nozzle 10 tends a considerable distance above the bottom wall of the smoke box as shown, although the invention is equally applicable to locomotives having a depressed chamber in the cylinder saddle surrounding the nozzle as shown in my Patent 15 No. 1,749,487, previously referred to. Depending from the lower end of the inner stack to a position below the mouth of the nozzle 18 is the flaring conical petticoat 20 which for convenience is made in several parts hinged and bolted together 20 as shown in Figure 2. Suitable mechanism 21 attaches the upper end of the petticoat to the lower end of the internal stack in a gas-tight manner so that all gases coming through the flues must pass beneath the reinforced lower edge 22 25 of the petticoat. This lower edge is preferably substantially horizontal. The upper end of the petticoat is of considerably larger diameter than the lower end of the internal stack as clearly shown in Figure 1. The lower edge of the petticoat is so spaced from the bottom of the smoke box that the area under it for the passage of flue gases is from 1.25 to 2.0 times the net flue area. This ensures a gas velocity adequate to compel 30 the sparks and cinders carried from the fire box 35 to pass up the stack so that no accumulation of cinders occurs in the smoke box. It is thus "self-clearing" or "self-cleaning."

Arranged within the petticoat and forming 40 preferably a cylindrical extension of the inner stack is the equivalent of the screen or netting of Patent No. 1,749,487. This is shown at 23 in Figures 1 and 2. Its upper end fits closely within the inner stack where it abuts beneath the extensions of the bolts 21' which prevent it from moving 45 upwardly under the force of the draft. Its diameter is such that it can be removed through the stack. Its lower end reinforced by a collar or band is shaped to closely fit the ring 25 on the bottom wall of the smoke box. Details of construction of this member forming important features of the present invention will be more fully described later.

To assist the screen 23 in breaking up cinders and sparks so that they all can be discharged from 55 the smoke box but only in sizes so small as to be harmless, are one or more baffles or targets 26 and 27. In most cases only the lower one, 26, will be necessary, but two, as shown, or even more may be used where it is found desirable. Each of 60 these baffles comprises a substantially flat sheet of suitable foraminous material such as netting, screen, reticulated metal, bars, rods, or the like, the plane of the whole being inclined at an angle of substantially 45° as shown in Figure 1 and 65 extending from side to side of the barrel 10 as seen in Figure 2. The lower baffle 26 is inclined from a point near the bottom of the front flue sheet upward toward the stack, preferably ending near the junction of the inner stack and the petticoat. The second baffle and any additional ones are used, may have an overlapping relationship to the first but extent higher up to ensure 70 cinders from the top-most flues being intercepted.

The construction and inclination of these baffles is such that they act as targets for the cin-

ders which issue with great velocity from the flues. Most cinders will be broken by the impact and fall through the perforations in the baffles, others more refractory will be thrown upwardly by the inclination of the baffles and be given additional time to cool before falling to the bottom of the smoke box where they were swept up by the high velocity gases passing under the lower edge of the petticoat and thrown with considerable force against the screen 23 or the inner 10 walls of the petticoat and further broken. If they are not reduced to a size suitable to pass through the screen 23 they may again fall back and are continuously thrown upwardly and dropped until they are cooled or broken to a size 15 suitable for passing through the screen and out of the stack with safety.

A baffle such as 26 is most effective in conjunction with the lower flues through which the major portion of the cinders pass and ensures 20 against any direct impact thereof on the screen 23 where it is exposed below the lower edge of the petticoat so that it is not so rapidly eroded as would be the case with direct impact of the cinders from the flues. A sufficient height of baffle 25 26 to intercept the cinders from the bottom four or five rows of flues is believed to be adequate for most purposes.

The so-called screen 23 of Figures 1 and 2 is novel. Instead of being constructed as a woven 30 netting it comprises a plurality of louvers. These can be struck up from a cylindrical sheet if desired, but it is preferred to build up the screen from a pair of rings 30 and 31, at the top and bottom respectively of the screen, to the inside 35 of which is attached by welding a plurality of strips 32 forming blades. These strips are approximately $\frac{1}{8}$ " by $\frac{1}{4}$ " and each blade is set at an angle to its corresponding tangent to the cylinder or end rings of from 30° to 60°. A convenient way of obtaining this inclination is shown 40 in Figures 3 and 4 where the ends 33 of the strips are twisted as at 34 so that where attached by welding to the end rings they are tangent thereto.

A modification of this construction is shown in Figure 5 where the end rings 30' have a horizontal flange which is stepped or notched as at 36 to provide surfaces of the proper inclination for the attachment of the blades 32' which in this 50 case are perfectly straight strips.

As shown in Figures 1 and 6, one or more reinforcing hoops 37 may surround the blades circumferentially and be welded thereto intermediate the ends thereof, thus confining them rigidly 55 against vibration and maintaining the blade spacing.

The purpose of this type of louvered screen is to impart a spiral motion to the gasses passing 60 upwardly from the bottom of the petticoat there- by throwing the sparks outwardly against the surrounding surface of the petticoat and against the spark arrester to pulverize them. It will be remembered that if the baffles 26 and 27 are also used they have already aided in this pulverization. 65 The louvered screen, however, has been found quite effective without the baffles.

The interior of the petticoat may be provided with ribs or the like to assist in pulverization of the spark thrown thereagainst by the whirling 70 motion imparted to the gases by the louver blades.

In Figure 6 is shown a modification of the screen or spark arrester in which the upper and lower bands 40 and 41 are connected by blades 42 which are somewhat inclined to the vertical as 75

well as given an angle to the tangents to the cylinder. This type of blade imparts a spiral helical movement to the gases and cinders, and since the openings between the blades face upward the 5 sparks are well broken before passing between the blades 42.

In Figures 7 and 8 is shown an arrangement combining the louvered construction of Figures 1 and 2 with sections of conventional screen or 10 netting. As seen in Figure 8, portions 43 and 44 are equipped with louvers and the intermediate portions 45 and 46 with netting. With this construction the cinders which are broken up against the louvers may readily pass through the netting 15 where the gas direction is more nearly radially inwardly.

In Figure 8 there are shown in addition the inside, vertical and radially disposed vanes or ribs 47 at the junctions of the louvers and netting, although they may be disposed in any desired manner within any of the forms of screens shown. It will be seen that with the 20 whirling action of the gases the cinders which pass within the screen will be thrown against these ribs and further broken and pulverized. The screen can thus be coarsened to prevent clogging and yet dangerously large cinders broken up before issuing from the stack.

Figure 9 shows a further combination of louvers 30 and screen wherein the central portion 50 is provided with louvered blades extending clear around the circumference attached to intermediate rings 51 between which and the end rings 52 are bands of netting 53. This provides passages 35 more nearly radially inwardly through the ends of the screen or spark arrester together with a whirl imparting section intermediate the ends.

In Figure 10 the arrangement is the reverse of that seen in Figure 9 with the netting band 55 in 40 the center and louvered end sections 56.

In order to insure the "self-clearing" feature of the smoke box the lower baffle 26 is spaced slightly above the floor of the smoke box so that the "pull" of the draft draws any sparks or cinders which fall behind this baffle toward the stack 45 where they are picked up and ejected.

The various combinations of louvers and netting may obviously be further combined or 50 changed to suit conditions in different types of locomotives with different shapes, sizes and relative proportions of the smoke box, stack and other parts.

Having thus described the invention, what is 55 claimed as new and desired to be secured by Letters Patent is:

1. A spark arrester assembly for locomotives comprising in combination, a smoke box, a smoke stack extending through a wall thereof, an exhaust nozzle at the bottom thereof, a reticulated, 60 tubular member adapted to be mounted within the smoke box as a continuation of the smoke stack and to extend around and below the exhaust nozzle, said member being formed of a plurality of louver blades extending lengthwise of the stack 65 and a flaring petticoat closely fitting the lower end of said stack surrounding the upper portion of said tubular member and spaced therefrom radially.

2. A spark arrester assembly for locomotives comprising in combination, a smoke box, a smoke stack extending through a wall thereof, an exhaust nozzle at the bottom thereof, a reticulated, 70 tubular member adapted to be mounted within the flue gas receiving smoke box as a pendant 75

continuation of the smoke stack, to extend over the exhaust nozzle and down to the bottom of the smoke box, said member being formed of a plurality of louver blades extending lengthwise of the stack, the plane of each blade extending at a 5 substantial angle to the corresponding tangent to the tubular member, a flaring petticoat surrounding and spaced from the upper portion of the said tubular member whereby flue gases are delivered substantially longitudinally thereof, said 10 member having a vertical height greater than one-half the vertical height of the smoke box.

3. A spark arrester assembly for locomotives having horizontal boiler flues entering a smoke box comprising in combination, a smoke stack 15 extending through the smoke box wall, an exhaust nozzle at the bottom of the smoke box, a reticulated, tubular member adapted to be mounted within the smoke box extending from the bottom thereof around the exhaust nozzle as 20 a continuation of the smoke stack, said member being formed of a plurality of louver blades extending lengthwise of the stack, the plane of each blade extending at a substantial angle to the corresponding tangent to the tubular member, a 25 flaring petticoat surrounding and spaced from the upper portion of the said member whereby flue gases are delivered substantially longitudinally thereof and means to intercept cinders directed toward the member from at least the 30 lower-most boiler flues.

4. A spark arrester assembly for locomotives having horizontal boiler flues entering a smoke box comprising in combination, a smoke stack extending through the smoke box wall, an exhaust 35 nozzle at the bottom of the smoke box, a reticulated, tubular member adapted to be mounted within the smoke box extending from the bottom thereof around the exhaust nozzle as a continuation of the smoke stack, said member being formed of a plurality of louver blades extending lengthwise of the stack, the plane of each blade extending at a substantial angle to the corresponding tangent to the tubular member, a flaring 40 petticoat surrounding and spaced from the upper portion of the said member whereby flue gases are delivered substantially longitudinally thereof and a baffle of foraminous material 45 between the boiler flues and the petticoat.

5. The combination with a locomotive smoke box, stack and exhaust nozzle, of a spark arrester of generally tubular form sized for insertion through the stack and for extension from the bottom thereof to the base of the smoke box 55 around said nozzle, a petticoat depending from said stack, surrounding the part of the arrester above the nozzle and serving to direct gases generally upwardly around the outside of the arrester, said arrester being formed of louver blades extending generally in the line of flow of the gases through the petticoat and each having its general plane intermediate that of a tangent plane and a radius plane intersecting in the periphery of the spark arrester tube. 60

6. The combination with a locomotive smoke box, forward flue sheet, stack and exhaust nozzle, of a spark arrester of generally tubular form sized for insertion through the stack and for extension from the bottom thereof to the base of the smoke 70 box around said nozzle, a petticoat depending from said stack, surrounding the part of the arrester above the nozzle and serving to direct gases generally upwardly around the outside of the arrester, said arrester comprising longitudi- 75

- nally extending, circumferentially spaced blades, each having its general plane inclined to a tangent to the arrester passing through the blade, and a forwardly and upwardly inclined perforated 5 baffle between the flue sheet and stack, said baffle extending across the smoke box and being arranged to intercept cinders directed toward that portion of the arrester extending below the petticoat.
10. 7. The combination with a locomotive smoke box, forward flue sheet, stack and exhaust nozzle, of a perforated tubular spark arrester extending from the base of the smoke box to mid-height thereof around the nozzle the upper end 15 of the arrester being contiguous to the stack, and a baffle extending entirely across the smoke box and inclined forwardly from a point near the flue sheet to deflect all cinders from the lower flues upwardly away from said arrester, said baffle having openings therethrough for the passage of gases.
8. The combination with a locomotive smoke box, forward flue sheet, stack, inner stack projection and exhaust nozzle, of a perforated tubular spark arrester extending from the base of the smoke box to mid-height thereof around the nozzle the upper end of the arrester being contiguous to the stack projection, and a plurality 20 of spaced, perforated baffles extending one above the other across the smoke box between the flue sheet and stack projection, the lowermost baffle clearing the bottom of the smoke box near the flue sheet and being inclined forwardly and upwardly.
30. 9. A spark arrester for use in locomotives between the exhaust nozzle and stack comprising a pair of spaced rings, spaced flat louver blades extending between said rings, each blade having its ends attached to said rings, the said ends being substantially tangential to said rings, and a 35 twisted portion in each blade adjacent each end to position the intermediate portion at a substantial angle to said ends to impart a whirling motion to gases passing to and through the louvers.
40. 10. A spark arrester for use in locomotives between the exhaust nozzle and stack comprising a pair of spaced rings, spaced flat louver blades extending between said rings, each blade having its ends attached to said rings, the said ends being substantially tangential to said rings, and a 45 twisted portion in each blade adjacent each end to position the intermediate portion at a substantial angle to said ends to impart a whirling motion to gases passing to and through the louvers and a substantially radial vane in said arrester to break up cinders thrown against it by said whirling gases.
50. 11. A spark arrester for use in locomotives between the exhaust nozzle and stack comprising a pair of spaced rings, spaced flat louver blades 55 extending between said rings, each blade having its ends attached to said rings, the said ends being substantially tangential to said rings, and a twisted portion in each blade adjacent each end to position the intermediate portion at a substantial angle to said ends to impart a whirling motion to gases passing to and through the louvers and a plurality of substantially radial vanes extending inwardly from the periphery of said arrester to be impacted by cinders passing between the louvers.
5. 12. The combination with a locomotive smoke box, forward flue sheet, stack and exhaust nozzle, of a spark arrester of generally tubular form sized for insertion through the stack and for extension 15 from the bottom thereof to the base of the stack around said nozzle, a petticoat depending from said stack, surrounding the part of the arrester above the nozzle and serving to direct gases generally upwardly around the outside of the 20 arrester, said arrester comprising longitudinally extending, circumferentially spaced blades, each having its general plane inclined to a tangent to the arrester passing through the blade, and a forwardly and upwardly inclined perforated baffle 25 between the flue sheet and stack, said baffle extending across the smoke box and being arranged to intercept cinders directed toward that portion of the arrester extending below the petticoat, the lower edge of said petticoat being so spaced from the bottom of the smoke box that the area for passage of gases thereunder is between 1.2 and 2.0 times the total flue area of the boiler of the locomotive whereby the gas velocity is adequate 30 to keep the smoke box clear of cinders at all 35 times.
13. In a locomotive having a smoke box, front flue sheet with horizontal flues extending therethrough in rows, stack and exhaust nozzle located on the floor of the smoke box, a reticulated cinder baffle plate between the front flue sheet and the axis of the stack, said baffle being located to intercept cinders passing through at least the four bottom-most rows of flues in the flue sheet but spaced sufficiently above the bottom of the 40 smoke box to prevent clogging thereof beneath the baffle by the broken cinders passing through the baffle.
45. 14. In a locomotive having a smoke box, front flue sheet with horizontal flues extending therethrough in rows, stack and exhaust nozzle located on the floor of the smoke box, a reticulated cinder baffle plate between the front flue sheet and the axis of the stack, said baffle being located to intercept cinders passing through at least the four bottom-most rows of flues in the flue sheet and inclined forwardly and upwardly from a position 50 near but above the floor of the smoke box just forward of the said flue sheet.

60 WILLIAM F. KIESEL, JR.
